(57) **CLAIM**

The ornamental design for a bench, as shown and described.

DESCRIPTION

FIG. 1 is a perspective view of the bench of the present invention;

FIG. 2 is a front elevation view thereof, the rear elevation view being identical thereto;

FIG. 3 is a right side elevation view thereof, the left side elevation view being identical thereto; and,

FIG. 4 is a top plan view thereof.

The broken lines in the figures are for purposes of illustrating environmental structure only and form no part of the claimed invention.
